(57) **CLAIM**

I claim the ornamental design for an elastic cable holder, as shown and described.

DESCRIPTION

FIG. 1 is a perspective view of an elastic cable holder, showing a first embodiment of my new design;

FIG. 2 is a front elevational view of FIG. 1, the rear elevational view being a mirror image thereof;

FIG. 3 is a left-side elevational view of FIG. 1, the right-side elevational view being a mirror image thereof;

FIG. 4 is a top plan view of FIG. 1;

FIG. 5 is a bottom plan view of FIG. 1;

FIG. 6 is a perspective view of a second embodiment thereof;

FIG. 7 is a front elevational view of FIG. 6, the rear elevational view being a mirror image thereof;

FIG. 8 is a left-side elevational view of FIG. 6, the right-side elevational view being a mirror image thereof;

FIG. 9 is a top plan view of FIG. 6; and,

FIG. 10 is a bottom plan view of FIG. 6.

The broken lines showing cords in FIG. 6 depict environmental matter and form no part of the claimed design. The remaining broken lines represent portions of the cable holder that form no part of the claimed design.
